DESIGN FOR A BICYCLE TANK

John R. Morgan, Oak Park, Ill., assignor to Sears, Roebuck and Co., Chicago, Ill., a corporation of New York

Application October 8, 1937, Serial No. 72,072

Term of patent 7 years

To all whom it may concern:

Be it known that I, John R. Morgan, a citizen of the Republic of Guatemala, residing at Oak Park, in the county of Cook and State of Illinois, have invented a new, original, and ornamental Design for a Bicycle Tank, of which the following is a specification, reference being had to the accompanying drawing, forming a part thereof.

Fig. 1 is a top plan view of a bicycle tank embodying my new design.

Fig. 2 is a side elevational view of the same.

Figs. 3-10 inclusive are sectional views taken substantially along the lines 3—3, 4—4, 5—5, 6—6, 7—7, 8—8, 9—9, 10—10 of Fig. 2.

I claim:

The ornamental design for a bicycle tank as shown.

JOHN R. MORGAN.
